DESIGN FOR A SPOON

Albert J. Thompson, Long Beach, Calif.

Application October 14, 1933, Serial No. 49,488

Term of patent 3½ years

To all whom it may concern:

Be it known that I, ALBERT J. THOMPSON, a citizen of the United States, and a resident of Long Beach, in the county of Los Angeles and State of California, have invented a new, original, and ornamental Design for a Spoon, of which the following is a specification, reference being had to the accompanying drawing, forming a part thereof:

I claim:

The ornamental design for a spoon substantially as shown.

ALBERT J. THOMPSON.
